UNITED STATES PATENT OFFICE

EDWIN H. STEEDMAN, OF ST. LOUIS, MISSOURI, ASSIGNOR TO CURTIS MANUFACTURING COMPANY, OF WELLSTON, MISSOURI, A CORPORATION OF MISSOURI

LUBRICATING SYSTEM FOR PISTON MACHINES

Application filed June 2, 1927. Serial No. 196,104.

This invention relates to lubricating systems for machines of the type which comprise a reciprocating piston joined by means of a connecting rod to a crank arm on a rotating shaft, such, for example, as compressors, internal combustion engines, reciprocating pumps, steam engines, etc.

One object of my invention is to provide a lubricating system or apparatus for machines of the general type mentioned, that is of simple construction, reliable in operation and of such design that an adequate supply of oil is assured for the parts of the machine that require practically constant or continuous lubrication when the machine is in operation.

Another object is to provide a lubricating apparatus for the crank pin of a piston machine, which is of such design that an excessive quantity of oil will not be supplied to the cylinder when the machine is operated at a high speed.

Another object is to provide a positive lubricating system or apparatus for a bearing between a connecting rod and a crank arm, that is not dependent for its successful operation on valves or other elements that are liable to fail when the machine is in operation.

And still another object is to provide a lubricating system or apparatus that can be easily adjusted or designed so as to supply just the required amount of oil to the bearings or parts with which it co-operates and whose elements are so constructed and arranged that they are easily accessible for inspection, repair or cleaning. Other objects and desirable features of my invention will be hereinafter pointed out.

To this end I have devised a lubricating system or apparatus that comprises a rotatable member combined with the crank shaft of the machine of which the apparatus forms a part and provided with an oil chamber of such design that the centrifugal force produced by the rotary movement of said member forces oil into said chamber and exerts pressure on the oil in said chamber in a direction tending to positively force said oil through a duct, passageway or conduit which leads to the bearing between the connecting

rod and the crank arm on said shaft, an inclined distributing surface adjacent said oil chamber designed so that centrifugal force causes oil on said inclined surface to travel towards said chamber, and means for supplying or delivering oil to said distributing surface. The oil chamber in said rotatable member can be formed in various ways. Generally, said oil chamber will be formed by an annular or substantially annular, open groove formed in a surface of said rotatable member that is disposed transversely of and at substantially right angles to the axis of the crank shaft, and said chamber will have an outer wall that is undercut or shaped so that the centrifugal force also overcomes the tendency of the oil to escape laterally from said chamber when the machine is in operation. My invention is applicable to single cylinder and multiple cylinder machines, and when it is embodied in a multiple cylinder machine, the rotatable member in which the oil chamber or pocket is formed is preferably arranged or mounted on the crank shaft at a point between adjacent connecting rods and is provided with two oil chambers of the kind mentioned and two oil ducts or passageways that lead from said chambers to the respective bearings of the connecting rods that surround the crank pins on the shaft which impart movement to said connecting rods.

In view of the fact that so many different types or kinds of means can be used to supply oil to the centrifugal pressure chamber or groove of the rotatable member on the crank shaft, I have illustrated in the drawings several forms of my invention, all of which operate on the same general principle, but each of which is equipped with a slightly different means for keeping the centrifugal pressure chamber supplied with oil.

Figure 1 is a side elevational view, partly broken away, of the crank case of a two-cylinder compressor equipped with a lubricating system constructed in accordance with my invention.

Figure 1^a illustrates my improved lubricating system applied to a single cylinder compressor.

Figure 2 is an end view of said crank case,

partly in vertical section, on the line 2—2 of Figure 1, looking in the direction indicated by the arrows.

Figure 3 is an enlarged transverse sectional view of a portion of the rotatable member in which the centrifugal pressure chamber is formed.

Figure 4 is a longitudinal sectional view of a crank case, illustrating a form of my invention, in which the means used to supply oil to the centrifugal pressure chamber consists of a rotatable ring, partly submerged in the oil in the crank case and arranged in engagement with the member in which said chamber is formed.

Figure 5 is a transverse sectional view, taken on the line 5—5 of Figure 4.

Figure 6 is a fragmentary sectional view, illustrating a feature that can be added to a lubricating apparatus of the kind shown in Figures 4 and 5.

Figure 7 is a longitudinal sectional view of a crank case illustrating a form of my invention in which a plunger pump is used to supply oil to the centrifugal pressure chamber.

Figure 8 is a transverse sectional view, taken on the line 8—8 of Figure 7.

Figure 9 is a longitudinal sectional view of the crank case of a single cylinder machine embodying my invention, in which a rotary pump is used to supply oil to the centrifugal pressure chamber.

Figure 10 is a transverse sectional view, taken on the line 10—10 of Figure 9.

Figure 11 is a longitudinal sectional view of a crank case, illustrating a form of my invention in which oil is supplied to the centrifugal pressure chamber by gravity from an overhead trough or reservoir in the crank case.

Figure 12 is a transverse sectional view, taken on the line 12—12 of Figure 11; and

Figure 13 is a longitudinal sectional view of the crank case of a single cylinder machine embodying my invention, in which oil is fed to the centrifugal pressure chamber from an oil tank or container arranged on the outside of the crank case of the machine.

In the accompanying drawings which illustrate various forms of my invention, A designates the crank case of a compressor, internal combustion engine, reciprocating pump or other machine equipped with one or more cylinders whose pistons are joined by connecting rods B to the crank shaft C of the machine. The connecting rods of such machines are provided at their lower ends with bearings 1 that surround crank pins D on the crank shaft, and when the machine is in operation, it is essential that each crank pin or the connecting rod bearing with which it cooperates receive an adequate supply of oil. One of the main objects of my invention is to provide a lubricating system or apparatus of simple design that will positively

supply oil to the crank pin of such a machine without liability of causing the cylinder of the machine to receive an excessive supply of oil when the machine is operated at a high

70

Another object is to provide a lubricating apparatus for a crank pin or its co-operating connecting rod bearing that has the desirable characteristics of conventional pressure feed systems, but not the objectionable characteristics of such systems, i. e., liability of failure caused by sticking or breaking of spring-actuated valves or other delicate parts. In my improved lubricating system or apparatus

80

the oil that is used to lubricate the crank pin D is forced to said pin or to the connecting rod bearing 1 with which it co-operates by pressure produced by centrifugal force. This result can be attained in various ways without departing from the spirit of my invention, but in the preferred form of my invention, as herein illustrated, the crank shaft C of the machine has associated with same a rotatable member E that is provided with an oil chamber F from which an oil duct

85

or passageway 3 leads to the outer surface of the crank pin D, as shown in Figures 1, 1^a, 2 and 3. The member E can be formed integral with the crank shaft, or it can be detachably connected to the crank shaft, and when the invention is embodied in a multiple cylinder machine, as shown in Figure 1, the member E can consist of a substantially disk-shaped portion on the crank shaft C that is located between adjacent connecting rods B

90

and which forms portions of the crank arms on the crank shaft that carry the crank pins D. The member E is preferably arranged at right angles to the longitudinal axis of the crank shaft, and the peripheral edge of said member is bifurcated so as to form a slot 4 in same that has parallel, vertically-disposed side walls 5. Two centrifugal pressure chambers of the kind previously referred to, from which oil is forced through ducts that lead to the crank pins, are preferably formed by two annular grooves F in the side walls 5 of the slot in the member E, said grooves being preferably arranged in concentric relation with the axis of the crank shaft C for ease of construction. The grooves F are open at one side, as shown in Figure 3, so that they will communicate with the slot 4 in the member E, and the outer walls of said grooves F

95

are undercut or made of such shape that the opposed outer and inner walls x and y of each of said grooves will be disposed at such an angle to the vertical surfaces 5 on the member E in which said grooves are formed that the centrifugal force produced by the rotary movement of the member E will produce pressure in the grooves F that causes the oil in same to be fed to the ducts or passageways 3 that lead from said grooves to the crank pins D. When the crank shaft C is set in

100

110

115

120

125

130

operation any oil that may be on the vertically-disposed surfaces 5 of the member E will be thrown radially from the peripheral edge of the member E, but the oil in the open grooves F in said vertical faces 5 will be effectively prevented from escaping outwardly from said grooves by reason of the fact that centrifugal force and the undercut outer walls of said grooves combine or co-operate to hold the oil in the grooves F and exert pressure on said oil in a direction to force it positively through the ducts 3 leading to the crank pins.

Means is provided for automatically supplying oil to the oil pockets or pressure chambers formed by the grooves F in the member E, and in the form of my invention illustrated in Figures 1 and 2, the means just referred to consists of a rotatable wheel G submerged partly in a bath of oil and arranged in frictional engagement with inclined distributing surfaces 6 on the member E which are disposed at such angles that the oil supplied to said surfaces by the wheel G will travel by centrifugal force into the grooves F, as shown in Figure 3. The inclined, distributing surfaces 6 are arranged in concentric relation with the axis of rotation of the member E and form continuations of the inner walls y of the grooves F in the member E. My improved lubricating system is applicable to a single cylinder machine, and therefore, I have illustrated it in Figure 1^a in connection with a single cylinder compressor, the member E that carries the lubricated surface 6 being connected to the crank shaft.

The oil supply wheel G is arranged directly underneath the rotatable member E, so that a portion of the periphery of said wheel G will bear against the outwardly-inclined surfaces 6 on the member E. A weight, spring or other suitable means can be used for holding the wheel G in frictional engagement with the member E, and in the form of my invention illustrated in Figures 1 and 2, the wheel G is rotatable mounted on a lever 7 that is acted upon by a spring 8 that normally exerts pressure on said lever in a direction to hold the wheel G in engagement with the member E. The wheel G can be so disposed that a portion of same dips into the oil in the bottom of the crank case A, but preferably the wheel G is rotatably mounted in an oil receptacle 9 carried by the lever 7 and provided with one or more orifices 10 through which oil is supplied to the interior of said receptacle 9 from the bath of oil in the bottom of the crank case, said orifice 10 being so disposed that it is always below the level of the oil in the crank case. By varying the size of the orifice 10 or providing the oil holder 9 with an adjustable or calibrated orifice, the quantity of the oil which the wheel G supplies to the centrifugal pressure chamber in the member E can be accurately controlled.

In order to prevent sediment or foreign matter from collecting in the orifice or orifices 10 through which oil is supplied to the oil holder 9, a screen 11 is arranged over said orifice. The lever 7 that carries the oil holder 9 can be connected to any suitable portion of the crank case, but I prefer to attach the lever 7 and also the spring 8 to a removable hand hole plate on the crank case, as shown in Figure 2, so as to enable the oil wheel G and the oil holder 9 in which said wheel rotates to be removed bodily from the crank case for inspection, repair or cleaning.

The walls of the cylinder of the machine are lubricated preferably by the oil thrown by centrifugal force from the joints at the ends of the connecting rod bearings 1. The joints at the ends of the connecting rod bearings 1 are also utilized to supply oil by centrifugal force to oil distributing members 13 in the upper portion of the crank case A which are so constructed and arranged that the oil thrown against the underside of said members from the ends of the connecting rod bearings 1 will flow downwardly on said members and finally drip from same into oil holes 14 in the crank shaft bearings 15, as shown in Figure 1. In order to prevent excess of oil that may be on the vertically-disposed surfaces 5 of the member E from being thrown upwardly into the cylinders of the machine, and thus causing the cylinders to receive an excessive supply of oil, an oil guard 16 is arranged over the rotatable member E.

From the foregoing it will be seen that a lubricating system or apparatus of the construction above described insures oil being supplied to the cylinders of the machine, to the main crank shaft bearings and to the bearings on the connecting rods that surround the crank pins, the oil being supplied under pressure to the crank pins at such a rate and in such a manner as to make it practicable to operate the machine at a high speed without liability of causing the cylinders to receive an excessive supply of oil, as is liable to occur in a machine whose crank pins and cylinder walls are lubricated by splashing devices on the crank arms that dip into the bath of oil in the bottom of the crank case. In my improved lubricating system a fairly definite quantity of oil is supplied to the connecting rod bearing 1 by pressure produced by centrifugal force, and the oil which escapes from the ends of the connecting rod bearings 1 is used to lubricate the cylinder walls and to lubricate the main bearings of the crank shaft. Such a lubricating system is reliable in operation; it is inexpensive to construct and install and it is always easily accessible for inspection, repair or cleaning. In the above described form of my invention, as shown in Figures 1 and 2, and in the other forms of my invention which I am about to describe, I have shown the oil chamber F as

an annular groove for simplicity of manufacture. The oil chamber F, however, does not have to be continuous, or of annular form, but can be any kind of pocket, straight or curved, with undercut walls x and y formed in any manner and disposed at an angle to the surfaces 5, as previously described.

In the form of my invention shown in Figures 4 and 5, the means that is used to supply oil to the centrifugal pressure chamber of the member E consists of an oil ring G' positioned in the annular slot 4 in the member E and arranged so that the lower portion of said ring is normally submerged in the bath of oil in the bottom of the crank case, the weight of said ring G' causing it to be held in frictional engagement with the outwardly-inclined, distributing surfaces 6 on the member E that lead to the oil grooves F, said distributing surfaces being disposed in concentric relation with the axis of rotation of the member E. A roller 17 on the bottom of the crank case that laps over said ring may be used to prevent the ring G' from getting out of position.

If desired, co-operating teeth 18 can be formed on the inner side of the oil ring G' and on the bottom of the slot 4 in the member E, as shown in Figure 6, so as to positively rotate said oil ring and cause it to feed oil upwardly from the bath of oil in the crank case to the surfaces 6 of the member E. The structure shown in Figures 4, 5 and 6 is claimed specifically in my pending application for patent Serial No. 289,854, filed July 2, 1928.

In the form of my invention shown in Figures 7 and 8, a plunger pump G² is arranged in the crank case directly underneath the rotatable member E, and said member E is provided with a cam or is constructed in such a way that the rotary movement of said member actuates the piston of the pump G² and causes jets of oil to be projected upwardly onto the outwardly-inclined surfaces 6 which are disposed in concentric relation with the axis of rotation of the member E, the oil thrown onto said surfaces being carried outwardly and laterally into the grooves F in the member E, and thence into the ducts or passageways 3 that lead to the connecting rod bearings 1. As shown in Figures 7 and 8, a screen 9^a is arranged over the intake of the pump G², so as to prevent sediment or foreign matter from entering said pump and interfering with the operation of same.

In Figures 9 and 10 I have illustrated my invention embodied in a single cylinder machine in which the means used to supply oil to the centrifugal pressure chamber in the rotatable member E consists of a gear pump G³ operated by a gear 19 on the member E and provided with a discharge pipe 20 whose upper end is arranged above the slot 4 in the

member E, as shown more clearly in Figure 9, thereby causing oil to be taken from a source of supply and elevated to a point from which it will discharge or drop onto the distributing surfaces 6 of the member E, which distributing surfaces 6 are disposed in concentric relation with the axis of rotation of the member E.

In the form of my invention shown in Figures 11 and 12, the rotatable element of the apparatus in which the centrifugal pressure chamber is formed, is composed of a member E' detachably connected with the crank shaft and constructed from two parts that are connected together and held in operative relationship with the crank shaft by means of bolts 21. The member E' comprises a slot 4 and concentrically-disposed distributing surfaces of the kind previously described, and oil is supplied to said distributing surfaces from an oil holder or reservoir 22 arranged above said member and provided with a hole through which oil drips, the said reservoir being supplied with oil by an oil throwing device 23 on the member E' that dips into the bath of oil in the bottom of the crank case and throws some of the oil upwardly into the trough 22 at each cycle of operations of the crank shaft.

In the form of my invention illustrated in Figure 13 oil is supplied to a concentrically-disposed distributing surface 6 on the rotatable member E by an oil drip device 24 arranged above the member E in alignment with the slot 4 in same and connected with an oil reservoir or tank 25 that is arranged outside of the crank case. It is obvious that a reservoir could be located inside of the crank case, if desired.

Having thus described my invention, what I claim as new and desire to secure by Letters Patent is:

1. In a machine of the character described, a crank shaft provided with a crank pin, a connecting rod joined to said crank pin, a member on the crank shaft provided in its peripheral edge with a slot, an undercut oil groove in said member to which oil is supplied by centrifugal force from the inner surface of said slot, a duct or passageway leading from said groove to said crank pin, and an oil supplying wheel partially submerged in a bath of oil and contacting at its peripheral edge with the inner surface of said slot.

2. In a machine of the kind described, a crank shaft provided with a crank pin, a rotatable member combined with the crank shaft and provided with an undercut oil groove, a duct or passageway leading from said groove to said crank pin, and an oil wheel partly submerged in a bath of oil and arranged in engagement with said rotatable member for supplying oil to the oil groove in same.

3. In a machine of the character described, a crank shaft provided with a crank pin, a rotatable member combined with said crank shaft and provided with an oil groove constructed so that centrifugal force created by the rotary movement of said member tends to force oil into said groove and out through said oil duct to the crank pin, an oil supplying wheel arranged in engagement with said member for feeding oil to the groove in said member, a holder in which said oil wheel is rotatably mounted, and means for maintaining an approximately constant level of oil in said holder.
4. In a machine of the character described, a crank shaft provided with a crank pin, a rotatable member combined with said crank shaft and provided with an oil groove constructed so that centrifugal force created by the rotary movement of said member tends to force oil into said groove and into a duct leading to the crank pin, an oil supplying wheel arranged in engagement with said member for feeding oil to the groove in said member, a holder in which said oil wheel is rotatably mounted, means for maintaining an approximately constant level of oil in said holder, a spring-actuated lever that carries said holder, and a removable hand hole plate on the crank case of the machine that sustains said lever.
5. In a machine of the character described, a crank shaft provided with a pair of crank pins, connecting rods joined to said crank pins, a member on the crank shaft arranged between said connecting rods and provided in its peripheral edge with a slot whose inner edges are formed by oppositely-inclined surfaces that slope outwardly or away from the axis of rotation of the crank shaft, undercut oil grooves in said member to which oil is supplied by said oppositely-inclined surfaces, ducts or passageways leading from said grooves to said crank pins, and an oil supplying wheel partially submerged in a bath of oil and provided at its peripheral edge with surfaces that contact with the oppositely-inclined surfaces on said rotatable member.
6. In a machine of the kind described, a crank shaft provided with a crank pin, a rotatable member combined with the crank shaft and provided with a centrifugal pressure chamber, a duct or passageway leading from said chamber to said crank pin, an inclined surface on said rotatable member for delivering oil to said chamber, and an oil wheel partly submerged in a bath of oil and arranged in engagement with the inclined distributing surface on the rotatable member.

EDWIN H. STEEDMAN.
